UNITED STATES PATENT OFFICE.

WILLIAM H. OLSON, OF GREENFIELD, MASSACHUSETTS.

FILING-CABINET.

1,334,712.

Specification of Letters Patent. Patented Mar. 23, 1920.

Application filed September 26, 1919. Serial No. 326,448.

To all whom it may concern:

Be it known that I, WILLIAM H. OLSON, a subject of the King of Sweden, residing at Greenfield, county of Franklin, State of Massachusetts, have invented a certain new and useful Improvement in Filing-Cabinets, of which the following is a specification, reference being had therein to the accompanying drawings.

10 The invention relates to an improvement in filing cabinets. The object of the invention is to provide a filing cabinet having a plurality of drawers, and having automatic means for mechanically opening any one of 15 the drawers desired.

The invention consists substantially in providing a lock for the opening mechanism, means for releasing the lock, a movable indicator which can be adjusted to indicate visually the particular drawer that 20 it is desired to open, and means whereby the drawer opening mechanism is adjusted simultaneously with the indicator so that by simply releasing the lock the desired drawer 25 will be automatically opened.

The invention is especially intended for application to a cabinet for filing records for victrolas and the like. The invention, however, is not limited to use in connection 30 with a cabinet for filing records of that character, but it is obvious that it is adapted for application to a filing cabinet for papers, tools or any other articles desired, the respective drawers being of suitable form 35 to be adapted to the particular articles which the cabinet is to contain.

The invention will be fully understood from the following description when taken in connection with the accompanying drawings, and the novel features thereof will be 40 pointed out and clearly defined in the claims at the close of this specification.

In the drawings, Figure 1 is a front elevation, partly broken away, of a cabinet embodying the invention, showing the door 45 partially open.

Fig. 2 is a plan view.

Fig. 3 is a side elevation.

Fig. 4 is a section on line 4-4 of Fig. 2.

50 Fig. 5 is a section on line 5-5 of Fig. 3.

Referring now to the drawings, 1 represents the casing of a cabinet which is provided with a compartment 2 containing a plurality of slide drawers 3 mounted one 55 above the other and slidable on the slide cleats 4.

These drawers are readily movable in and out when the cabinet door is open. The cabinet is provided with a door 5 to close the front of the drawer compartment. 60 When the cabinet is used for filing records, the slides may be made up of skeleton form, as shown in Fig. 2, and preferably each slide has provided a vertical upwardly extending pin 6 in the middle of the slide to fit the 65 hole in the record, so as to hold the record from sliding around in the drawer. Preferably, the different drawers or slides are numbered consecutively in some conspicuous place, preferably on the front of the drawer, 70 as shown in Fig. 1 in which, beginning at the top, they are numbered from 1 to 12.

At one side of the compartment 2, there is another compartment 7 for inclosing some of the operating mechanism. A vertical 75 rocker shaft 8 is journaled in suitable bearings in the top bracket 9 and bottom bracket 10, which are respectively secured to the inside of the top and bottom of the casing. The rocker shaft 8 is non-circular, preferably 80 square in cross-section, except at its journal ends.

A feed screw 11 is journaled at top and bottom in suitable bearings, being shown as 85 journaled in bearings in the top and bottom brackets 9 and 10 which support the rocker shaft 8. Mounted on the feed screw 11 is a follower 12 which is tapped out to correspond with the threads on the feed screw 90 and which is moved up or down in accordance with the rotation in one direction or the other of the feed screw. This follower is provided with an arm 13 which at its outer end is bifurcated forming two ears 95 14-14. Each of these ears is formed with a circular aperture 15 extending vertically therethrough. These apertures form bearings for cylindrical slide blocks 16, which are rotatable within said apertures 15 and which are each formed with a non-circular 100 opening corresponding in contour with the cross-sectional contour of the non-circular rocker shaft 8. They have a sliding fit over said rocker shaft so that they may slide on said rocker shaft, and by reason of their 105 corresponding contour they are rotatable with said rocker shaft.

Mounted loosely on said rocker shaft between the ears 14-14 is a lever 17, the pivot end 18 of said lever being formed with a 110 non-circular opening through which the shaft 8 loosely passes, so that the lever 17

can slide up and down with the follower arm 13, but by reason of the non-circular form of the journal opening through which the shaft passes, said lever will rock in a horizontal plane when the shaft rocks. The slide blocks 16—16 are each formed with a flange 19 which respectively bear against the upper and under sides of the head of the lever to form washers and also to prevent the said slide blocks from slipping out of the ears. The lever 17 extends transversely of the drawers 3 just at the rear.

Journalized in the bearing 20 mounted in the side wall of the casing is a shaft 21, the inner end of which carries a beveled gear wheel 22, which meshes with a bevel gear 23 on the upper end of the feed screw 11. On the shaft 21 outside of the case, there is mounted a handle 24 which is preferably in the form of a knurled wheel, whereby said shaft 21 may be rotated. When the shaft 21 is rotated in one direction by said handle, namely in clockwise direction, as shown in the drawings, the rotation of the beveled gears 22 and 23 will be such as to rotate the feed screw 11 in a direction to cause the descent of the follower 12 and thereby to cause the descent of the lever 17. When the wheel handle 24 is rotated in the reverse direction, it will cause the feed screw to also rotate in the reverse direction and to cause the ascent of the follower 12 and the lever 17.

A coiled spring 25 is coiled around the rocker shaft 8 near its lower end, one end of said spring being made fast to the shaft and the other end being made fast to a stationary support. As shown in the drawings, the stationary end of the spring is fastened to a pin 26 rising from the bracket 10 in which is journaled the lower end of the rocker shaft. This spring is under tension and tends to relax, in doing which it will rotate the shaft 8 in a direction to throw the lever 17 forward into the dot-and-dash line position shown in Fig. 2. The said shaft, however, is normally held against yielding to the tension of the spring by means of a latch at its upper end. This latch, as shown, consists of a hook member 28 which engages with a pin 27 which projects laterally from the rocker shaft, the catch 28 being mounted on the lower end of a vertical slide pin 29, which slides in vertical bearings and projects up through the top of the case 1. A spring 30 normally retains the slide pin in its uppermost position to hold the catch 28 in locking position with relation to the latch pin 27. When the slide pin 29 is depressed it releases the hook 31 of the catch 28 from the latch pin 27 so that the rocker shaft 8 is free to respond to the stress of the spring 25. Preferably, the slide pin 29 is provided with a cap 32 which extends up

through a housing 33 on the top of the case 1, and forms a finger-piece for engagement by the finger in depressing the slide pin.

When the rocker shaft 8 rocks in response to the stress of the spring as already described, the lever 17 is swung forward with a sharp stroke and if at the time of the stroke it is directly behind one of the drawers 3, it will throw the drawer forward a sufficient distance into the dot-and-dash line position shown in Fig. 3 to open it out in a convenient position for the contents of the drawer to be extracted.

Means are provided whereby when the case is closed except for the front door, there may be easily determined by an indicator exposed on the outside just when, in the turning of the operating wheel 24, the ejector lever 17 will be brought into operative position with relation to the particular drawer that it is desired to open.

A rotary index wheel 34 is mounted on a shaft 35 and has a gear connection with the operating shaft 21, the gear connection shown being by means of a spur gear 36 carried by the index wheel 34 and a pinion 37 mounted on the operating shaft 21 which engages with said gear 36.

The periphery of the index wheel 34 has marked thereon a series of numbers from one upward corresponding in number with the numbers on the drawers 3 and spaced apart from each other. The gear for actuating the index wheel is so proportioned with relation to the mechanism which operates the feed screw that for each interval between the numbers on the index wheel, the ejector lever 17 will be raised or lowered a distance equal to the vertical distance between the middle of the back of one of the drawers and the middle of the next adjacent drawer above or below. In the top of the case 1 is a sight opening 38 having a glass cover 39 directly over the top of the index wheel. The numbers on the index wheel are so disposed that whenever a particular number is displayed through the sight opening the ejector lever 17 will be directly behind the correspondingly numbered drawer. If the slide pin 29 is then depressed by the finger, it will release the hook 31 of the catch 28 from the latch pin 27, thereby allowing the rocker shaft 8 to respond to the stress of the spring 25 and thereby the ejector lever 17 will engage the back side of the drawer corresponding to the number indicated on the index wheel and thrust it open. For instance, if it is desired to open the drawer numbered 7, the operating wheel 24 will be rotated until the figure 7 is disclosed through the sight opening, as shown in Fig. 2, then the slide pin 29 will be depressed by pushing down on the cap 32 of the slide pin 130

and the ejector lever 17, which will then be in position to engage the back side of the drawer 7, will thrust the drawer 7 open.

Whenever it is desired to close the drawer 5 it may be simply pushed back, and in being pushed back, it will swing backward the lever 17 which by reason of its connection with the rocker shaft 8 will turn the rocker shaft backward and swing the latch pin 27 10 around into engagement with the catch 28. The spring 30 connected with the slide pin 29 will have carried the slide pin upward after the downward pressure has been released at the time the drawer was opened. 15 The end of the hook 31 is inclined so as to form a cam face 40 which permits the latch pin 27 to ride over it and thereby to depress the catch until the pin 27 swings into the throat of the hook, whereupon the spring 30 20 will carry the slide pin upward again and hold the latch pin in locking engagement ready for the next operation. It is obvious that the form and location of the indicator disk may be varied as well as the operative 25 connection, and also that the particular mechanism for actuating the rocker shaft and indeed the mechanism for thrusting the drawer open controlled by the set of the indicator disk to correspond with the particular 30 drawer which it is desired to open, may be varied and still come within the scope of the invention; the particular mechanism shown and described being the best form at present known to me for accomplishing the 35 result above set forth. It is intended, however, to have the claims broadly cover the invention whatever may be the particular embodiment of the invention.

What I claim is,

1. A filing cabinet having a case, a plurality of slidable holders arranged in series in said case, a movable ejector, means for adjusting said ejector to bring it into operative relation to any one of the holders de-

45 sired, a tension device which tends to actuate the ejector to automatically open any of said holders for which the ejector is set, a detent for holding the ejector against yielding to the force of said tension device, and 50 means for releasing said detent at the will of the operator.

2. A filing cabinet having a case, a plurality of slidable holders arranged in series in said case, an ejector adjustable to varying 55 positions, means whereby said ejector may be brought into operative position with relation to any one of the slides desired, a spring under tension which tends to actuate the ejector to open one of the slides to which 60 it is adjusted, latch mechanism which normally holds the ejector in restraint against being actuated by said spring, and means for releasing said latch.

3. A filing cabinet having a case, a plurality 65 of slidable holders arranged in series

in said case, a rocker shaft journaled within said case and having an ejector lever adjustable thereon to varying positions, whereby said lever may be brought into operative position with relation to any one of the slides 70 desired, a spring under tension which tends to rock said shaft in a direction to actuate the ejector lever to open one of the slides to which it is adjusted, latch mechanism which normally holds the rocking lever in restraint against being actuated by said spring, and means for releasing said latch, said releasing means having operable connection which extends through the wall of the case into operative position on the exterior of the 75 case.

4. A filing cabinet having a case, a plurality of slidable holders arranged in series in said case, a rocker shaft journaled within said case and having an ejector lever adjustable thereon to varying positions, whereby said lever may be brought into operative position with relation to any one of the slides 80 desired, a spring under tension which tends to rock said shaft in a direction to actuate the 85 ejector lever to open one of the slides to which it is adjusted, latch mechanism which normally holds the rocking lever in restraint against being actuated by said spring, means for releasing said latch, said releasing means 90 having operable connection which extends through the wall of the case into operative position on the exterior of the case, means connected with said ejector lever inclosed within said case for adjusting said lever 95 with relation to said rocker shaft, and means located on the outer side of the case having operative connection extending into the interior of the case having driving connection with the mechanism for adjusting the 100 ejector lever.

5. A filing cabinet having a case, a plurality of slidable holders arranged in series in said case, a rocker shaft journaled within said case and having an ejector lever adjustable thereon to varying positions, whereby said lever may be brought into operative position with relation to any one of the slides desired, a spring under tension which tends to rock said shaft in a direction to 110 actuate the ejector lever to open one of the slides to which it is adjusted, latch mechanism which normally holds the rocking lever in restraint against being actuated by said spring, means for releasing said latch, 115 said releasing means having operable connection which extends through the wall of the case into operative position on the exterior of the case, means connected with said ejector lever inclosed within said case for adjusting said lever with relation to said rocker shaft, and means located on the outer side of the case having operative connection 120 extending into the interior of the case having driving connection with the mechanism 125

130

- for adjusting the ejector lever, a movable indicator actuated by the mechanism which adjusts the ejector and a sight opening in the case through which the indicator can be read, said indicator being graduated in such relation to the adjusting mechanism that the operation of the adjusting mechanism will cause the indicator to give indication of the position of the ejector lever.
10. A filing cabinet having a case, a plurality of slidable holders arranged in series in said case, a rocker shaft journaled within said case and having an ejector lever adjustable thereon to varying positions, where-
15 by said lever may be brought into operative position with relation to any one of the slides desired, a spring under tension which tends to rock said shaft in a direction to actuate the ejector lever to open one of the
20 slides to which it is adjusted, latch mechanism which normally holds the rocking lever in restraint against being actuated by said spring, means for releasing said latch, said releasing means consisting of a slidable pin
25 connected with the latch and extending through the wall of the case, a spring which normally holds the latch hook in engagement with a projection on the rocker shaft and which is released by the depression of
30 the pin, said latch having a cam face which permits the projection on the rocker shaft to ride back into operative connection with the latch hook when the rocker shaft is turned in reverse direction, and said ejector lever being in position to be engaged and
35 rocked in the reverse direction when the slide is manually pushed into closed position, thereby again locking the slide in its closed position.
40. A filing cabinet having a case, a plurality of slidable holders arranged in series in said case, a tension actuated ejector which normally tends to thrust outward one of the holders, means for adjusting said ejector to bring it into operative relation to any one
45 of the slidable holders desired, means for normally holding the ejector actuating mechanism in restraint, and means for releasing the restraint at the will of the operator.
50. A filing cabinet having a case, a plurality of slidable holders arranged in series in said case, a tension actuated ejector which normally tends to thrust outward one of the
55 holders, means for adjusting said ejector to bring it into operative relation to any one of the slidable holders desired, means for normally holding the ejector actuating mechanism in restraint, and a finger actuated
60 member for releasing the restraint upon the ejector thereby rendering the ejector automatically operative.
65. A filing cabinet having a case, a plurality of slidable holders arranged in vertical series in said case, a vertical rotary feed

screw inclosed in said case, a follower mounted on said feed screw having threaded connection therewith whereby the rotation of the feed screw raises and lowers said follower according to the rotation of the direction of the feed screw, an ejector lever mounted in said follower and projecting in the rear of the said holders and which by the rotation of the said feed screw may be brought into operative position with relation to any one of the said holders, a vertical rocker shaft which passes loosely through said ejector lever, said ejector being mounted on said rocker shaft in such manner that it is slidable thereon but rotates therewith, a tension device connected with said rocker shaft and tending to turn the rocker shaft in a direction to swing the ejector forward to thrust one of the said holders into open position, a detent which normally restrains said rocker shaft from turning and a tripping device connected with said detent and projecting to the outside of the case, whereby the operator may release the detent and allow the ejector to be actuated.

10. A filing cabinet having a case, a plurality of slidable holders arranged in vertical series in said case, a vertical rotary feed screw inclosed in said case, a follower mounted on said feed screw having threaded connection therewith whereby the rotation of the feed screw raises and lowers the follower according to the direction of the rotation of the feed screw, an ejector lever mounted on said follower and projecting in the rear of the said holders and which by the rotation of the said feed screw may be brought into operative position with relation to any one of the said holders, a vertical rocker shaft which passes loosely through said ejector, 95 said ejector being mounted on said rocker shaft in such manner that it is slidable thereon but rotates therewith, a tension device connected with said rocker shaft and tending to turn the rocker shaft in a direction to swing the ejector forward to thrust one of the said holders into open position, a 100 detent which normally restrains said rocker shaft from turning, and a tripping device connected with said detent and projecting to the outside of the case whereby the operator may release the detent and allow the ejector to be actuated, 105

110

115

120

125

130

sight opening will indicate the particular holder which is in alinement with the ejector.

11. A filing cabinet having a case, a plurality of slidable holders arranged in series in said case, a rotary feed screw, means for rotating said feed screw, a follower mounted on said feed screw having threaded connection therewith whereby the rotation of the feed screw raises and lowers the follower according to the direction of rotation of the feed screw, an ejector member mounted on said follower which by the rotation of the said feed screw may be brought into operative position with relation to any one of the said holders, tension means which tends to actuate the ejector to open any one of said holders for which the ejector is set, means for holding said ejector in restraint, and means for releasing said restraint and rendering the ejector operative.

12. A filing cabinet having a case, a plurality of slidable holders arranged in series in said case, a rotary feed screw, means for rotating said feed screw, a follower mounted on said feed screw having threaded connection therewith whereby the rotation of the feed screw raises and lowers the follower according to the direction of rotation of the feed screw, an ejector member mounted on said follower which by the rotation of the said feed screw may be brought into operative position with relation to any one of the said holders, tension means which tends to actuate the ejector to open any one of said holders for which the ejector is set, means for holding said ejector in restraint, means for releasing said restraint and rendering the

ejector operative, a movable indicator having markings thereon to indicate the different holders, a sight opening in said case through which the various markings on the indicator may be read, and means whereby the actuating mechanism for the feed screw also actuates the said indicator, said operating connections being so timed with relation to each other that the particular marking exposed at the sight opening will correspond with the particular holder which for the time being is in operative relation to the ejector.

13. A filing cabinet having a case, a plurality of slidable holders arranged in series in said case, a rotary feed screw, means for rotating said feed screw, a shaft having gear connection with said feed screw and projecting outside of the case, means connected with said shaft whereby it may be rotated at the will of the operator, a follower mounted on said feed screw having threaded connection therewith whereby the rotation of the feed screw raises and lowers the follower according to the direction of rotation of the feed screw, an ejector member mounted on said follower which by the rotation of the said feed screw may be brought into operative position with relation to any one of the said holders, tension means which tends to actuate the ejector to open any one of said holders for which the ejector is set, means for holding said ejector in restraint, and means for releasing said restraint and rendering the ejector operative.

In testimony whereof I affix my signature.
WILLIAM H. OLSON.
